UNITED STATES PATENT OFFICE.

JAFEW S. VAN BUREN, OF ALBANY, NEW YORK, ASSIGNOR TO THE RATHBONE, SARD & COMPANY, OF SAME PLACE.

DESIGN FOR A TOP SHELF FOR STOVES.

SPECIFICATION forming part of Design No. 32,708, dated May 22, 1900.

Application filed April 21, 1900. Serial No. 13,818. Term of patent 7 years.

To all whom it may concern:

Be it known that I, JAFEW S. VAN BUREN, a citizen of the United States, residing at Albany, in the county of Albany and State of New York, have invented and produced a new and original Design for Top Shelves for Stoves, of which the following is a specification, reference being had to the accompanying drawing, forming a part thereof.

10 The figure in the drawing is a plan view of a top shelf, showing my new design.

As shown in the drawing, the leading or material feature of my design is the open scrollwork A in a frame-like structure B, having the shape and ornamentation shown. The rear edge of the shelf is straight and has

two lugs C projecting therefrom. The corners of the shelf are rounded and the sides and front are curved slightly outward.

Having fully described my invention, what I claim as new, and desire to secure by Letters Patent, is—

The design for a top shelf for a stove, as herein shown and described.

In testimony whereof I have signed my name to this specification in the presence of two subscribing witnesses.

JAFEW S. VAN BUREN.
